UNITED STATES PATENT OFFICE.

JOHN A. ROBERTSON, OF ROCHESTER, NEW YORK, ASSIGNOR TO EASTMAN KODAK COMPANY, OF ROCHESTER, NEW YORK, A CORPORATION OF NEW YORK.

FILM-CARTRIDGE.

1,170,674.

Specification of Letters Patent. Patented Feb. 8, 1916.

Application filed September 25, 1912. Serial No. 722,165.

To all whom it may concern:

Be it known that I, JOHN A. ROBERTSON, of Rochester, in the county of Monroe and State of New York, have invented certain new and useful Improvements in Film-Cartridges; and I do hereby declare the following to be a full, clear, and exact description of the same, reference being had to the accompanying drawings, forming a part of this specification, and to the reference-numerals marked thereon.

My present invention relates to photography and more particularly to photographic film rolls or cartridges, and it has for its object to provide a construction of such devices whereby as the film and its paper or other protective backing is drawn from one spool onto the other during exposure in the camera it will be necessarily drawn taut and true to occupy a flat position in the focal plane.

To these and other ends the invention consists in certain improvements and combinations of parts all as will be hereinafter more fully described, the novel features being pointed out in the claims at the end of the specification.

In the drawing: Figure 1 is a perspective view of a photographic film roll constructed in accordance with and illustrating one embodiment of my invention, the outer end thereof being partially unrolled; Fig. 2 is an elevation thereof, and Fig. 3 is a section through a camera in which the film roll is being unwound from a feed spool onto a winding spool during the process of exposure.

Similar reference numerals throughout the several figures indicate the same parts.

As to its general features, the cartridge of the present invention may be constructed as usual, that is, to embody a roll preferably wound about a suitable spool or center 1 and consisting of a strip of flexible film 2 or sensitized material 2 and a protective backing strip 3 usually of black paper superposed thereon, the backing being slightly wider than the film strip and quite a little longer. The outer end of the film is attached to the backing in any suitable manner as by a paster 4 and beyond this point of attachment the end 5 of the backing constitutes the outer convolution and final covering of the roll as well as a means of attachment to the winding spool.

Inasmuch as the film strip is wound inside of the backing strip, though both are wound together, the convolutions of the backing strip are always longer than the corresponding convolutions of the film strip being of a greater circumference. In other words, a revolution of the winding spool 6 (Fig. 3) takes up a greater length of backing than it does film. The result is that in any film roll of this kind there is a relative creeping movement of the film with respect to the backing so that though the backing be taut the film will be loose and have a tendency to sag or bulge. This may be compensated for, of course, when the end of the unrolled film is reached either by leaving such end free in the beginning and attaching it after unrolling or by providing a sliding or adjustable connection between the two. However, the damage is done during the process of unrolling as the film is exposed at that time and if it bulges or buckles all parts of the negative will not be in focus even though the backing is drawn taut by reason of the fact that it is the backing that is under tension from the winding roll and which is causing the rotation of the feed roll. In the practice of my present invention I therefore transfer the winding tension from the backing to the film itself. To this end, I provide the backing at a point intermediate the ends of the film strips and preferably near the outer or attached end so that it will follow the film end upon the winding spool, with an extensible portion 7 that yields sufficiently to prevent the backing from assuming the strain further than its point of attachment to the film and which transfers the strain to the latter as will be seen from inspection of Fig. 3. The extensible portion 7 of the backing may be conveniently and inexpensively formed by simply creasing the backing strip transversely and folding over a double portion thereof in a manner clearly shown by the drawings. When so formed, it will wind close on the roll and yet give ample additional length to the backing to overcome the shortening of the latter relatively to the film as above explained.

Of course, differences either way in the relative thicknesses of the film and backing either aggravate or relieve the tendencies pointed out to a greater or less extent but they are very much aggravated when the convolutions on the winding spool are of

small diameter as is the case with the initial windings upon a spool that has a very small core or drum, in which circumstance, my invention will be found of great benefit.

5 For instance, in Fig. 3 where such a situation is presented the excess of backing length over film length in the same convolution taken up during one revolution of the winding spool is greater than the corresponding 10 inequality in the two elements resulting from the proportional unwinding of the feed spool. Thus, were it not for the extensible portion 7 the backing would be drawn tight and the slack in the film would increase, this 15 effect being cumulative though to a decreasing degree up to the time that the two rolls become of the same size, which is one of the reasons that I prefer to locate the extensible portion of the backing near the advancing or 20 outer end of the film. After the winding roll becomes the larger and the feed roll the smaller a reverse action takes place which tends to take up some of the looseness in the film but as far as the tightening of the inner 25 end of the backing strip is concerned, the slipping of the last convolutions on the feed spool can usually be relied upon to take care of this.

I claim as my invention:

30 1. As an article of manufacture, an un-

exposed photographic film cartridge embodying a backing strip, and a film strip having one end attached thereto, the backing strip being provided, intermediate the ends of the film strip, with a relatively easily longitudinally expansible section.

2. As an article of manufacture, a photographic film cartridge embodying a backing strip and a film strip having one end attached thereto, the backing strip being provided with an extensible portion at a point intermediate the ends of the film strip formed by a doubled crease or fold made transversely of the backing strip.

3. As an article of manufacture, an unexposed photographic film cartridge embodying a backing strip and a film strip wound together to form a roll with the backing strip outside, the outer end of the film strip being attached to the backing strip and the latter being provided, intermediate the ends of the film strip and adjacent the outer attached end of the film strip, with a relatively easily longitudinally expansible section.

JOHN A. ROBERTSON.
